(57) **CLAIM**

The ornamental design for a bottle as shown and described.

DESCRIPTION

FIG. 1 is an exploded perspective view of a bottle showing our new design with the top separated from the bottom;

FIG. 2 is a front elevation view thereof;

FIG. 3 is a rear elevation view thereof;

FIG. 4 is a left side elevation view thereof;

FIG. 5 is a right side elevation view thereof;

FIG. 6 is top view thereof;

FIG. 7 is bottom view thereof;

FIG. 8 is a perspective view of a bottle showing our new design with the top attached to the bottom;

FIG. 9 is a front elevation view thereof;

FIG. 10 is a rear elevation view thereof;

FIG. 11 is a left side elevation view thereof;

FIG. 12 is a right side elevation view thereof;

FIG. 13 is top view thereof; and,

FIG. 14 is bottom view thereof.

The dotted lines represent portions of the bottle that form no part of the claimed design.

1 Claim, 9 Drawing Sheets
